UNITED STATES PATENT OFFICE.

JULIEN STRANDERS, OF LONDON, ENGLAND, ASSIGNOR TO HARRY B. KRUGER, OF NEW YORK, N. Y.

DISPLAY STAND.

Application filed February 7, 1924. Serial No. 691,085.

The present invention relates to improvements in display stands, and it more particularly relates to a type of stand in which a number of display panels are associated together and preferably for the sake of commercial advantage cut from a single blank, for instance, of paper or cardboard, and so set up as to provide a plurality of display surfaces in conjunction with a compartment 5 or space preferably centrally located in a conspicuous position where an actual article of commerce may be supported and which serves, by its presence and weight, in conjunction with the peculiar construction 10 of the stand parts, to hold the several panels in a set up condition and against any likelihood of their collapsing or becoming so displaced or dislocated as to detract from or in any wise lessen the value of the display.

It is an object of the present invention to provide for the display of commercial articles in conjunction with various panels of a stand which may exhibit, for instance, advertising, printing or reading matter in connection with further displays of a pictorial nature, all of which have relation to the particular commercial article advertised by the display, and which may create suggestions as to its use.

Viewed in another aspect, the invention consists in the economic utilization of all parts of a display blank to form an attractive advertising medium in which the article of commerce such, for instance, as a can of milk or the like, may be supported at an elevation above the counter or other surface upon which the stand is placed in a conspicuous position where it will attract the eye of a prospective purchaser and in which the article is held on a supporting bottom or ledge which further acts to lock the various members of the stand in the position in which they are set up, and the stand as a whole being capable of ready setting up or collapse and being of an inexpensive construction.

With the foregoing and other objects in view, the invention will be more fully described hereinafter, and will be more particularly pointed out in the claim appended hereto.

In the drawings, wherein like symbols refer to like or corresponding parts throughout the several views,

Fig. 1 is a plan view of a blank cut out 55 in accordance with the present invention;

Fig. 2 is a perspective view of the blank set up as a display stand and exhibiting the article of commerce in connection therewith;

Fig. 3 is a top plan view of the set up 60 stand;

Fig. 4 is an end view thereof;

Fig. 5 is a vertical sectional view taken on the line 5—5 of Figure 3; and

Fig. 6 is a horizontal sectional view taken 65 or the line 6—6 in Figure 4.

Referring more particularly to the drawings, 1 designates a main and rear display panel which forms the major portion of the upper part of the blank of pasteboard or 70 other material out of which the blank may be made, and 2 and 3 represent the front or ancillary display panels which lie forwardly of the main and rear panel 1 and are foldably and permanently associated with the 75 latter through the medium of connecting webs or portions 4 and 5. The webs 4 and 5, and likewise the front panels 2 and 3, are cut out from the lower portion of the blank, the webs lying inwardly of the panels 2 80 and 3.

The webs 4 and 5 are foldable forwardly of the blank along score lines 6 and 7 which connect the webs with a central main supporting leg 8 which depends from the rear panel 1 centrally thereof and extends downwardly to the supporting surface. Lines of scoring 9 and 10 are also provided between respectively the webs 4 and 5 and the front display panels 2 and 3 on which the latter 90 are folded rearwardly so as to lie substantially parallel to and forwardly of the main and rear panel 1 as will be most clearly seen from an inspection of Figs. 2 and 3. Suitable configurations are cut out or otherwise 95 wrought upon the front panels 2 and 3. For instance, the panel 2 is irregularly serrated along its upper portion and provided with associated pictorial matter to represent a dish containing a tomato embellished with 100 lettuce and having a dressing poured over the same; while the companion display panel

3 at the opposite side of the stand is cut out, fashioned and colored or otherwise operated upon to give the representation of a pan in which, for instance, the dressing on 5 the tomato may be made by use of the commercial article within the can 11 placed between the two connecting webs 4 and 5 and which constitutes the articles of commerce advertised by the display. This may, for instance, be a can of milk which is held at an elevation above the lower supporting members of the stand, and which consequently is in a conspicuous position and is centrally located between the displays on the panels 2 10 and 3 and the display on the rear panel 1.

The can or other article 11 is held directly on a supporting bottom or ledge 12 cut out on three sides of the leg 8 and provided with side wings 13 and 14 which project into and appropriate parts of the connecting webs 4 and 5 at substantially their central portions, slits 15 and 16 being made in the upper portions of the supporting bottom or ledge 12 between the same and the wings 13 and 14 and lying substantially in line with the score lines 6 and 7 to the end that these slits 15 and 16, when the supporting ledge or bottom 12 is folded forwardly in the manner represented in Figs. 2, 4, 5 25 and 6, may be engaged at opposite sides of the webs 4 and 5, thus effectively securing the webs against a pivotal or swinging movement in either direction which might otherwise occur due to their hinging upon the score lines 6 and 7. Moreover, the removal of portions of the webs 4 and 5 to create the wings 13 and 14 of the supporting ledge or bottom is productive of shoulders 17 30 and 18 in the webs 4 and 5 on which the imperforate solid parts of the supporting ledge or bottom just below the slits 15 and 16 may be received when such supporting ledge or bottom is folded into the horizontal position. This imperforate part of course forms 40 the main support for the can or receptacle 11 and it is placed thereon so that the weight of the can will not tend to bend down or distort the forward portion of the ledge. 45

A line of scoring 19 is made between the 50 leg 6 and the supporting bottom or ledge 12 for convenience in folding it over and to indicate where this fold must be made in order to have it properly cooperate with the other associated portions of the stand.

55 Of course, it is to be understood that for purposes of producing display configurations on the panels 2 and 3 that the material of the connecting webs 4 and 5 may be drawn upon to a limited extent, and, for instance, a portion of the dish on the panel 2 is completed by appropriating a part of the material of the connecting web 4, and in like manner the pan on the panel 3 extends at one edge for a considerable distance into 60 the supporting web 5. These appropriated 65

portions of the webs 4 and 5 are left free of any score lines so that the appropriated part is made to lie in the same plane with the display panel and is folded with it.

In the manufacture of the stand, suitable 70 stamping or cutting machinery may be employed to produce the blank as shown in Fig. 1 in a single operation. The material may be cardboard or the like, and as a consequence of its material and the simplicity of 75 its manufacture, the stand becomes at once an extremely inexpensive and effective means of advertising. The blanks may be shipped to their point of use in the flat condition and so produced there is no mistaking 80 the manner of their assembly and setting up.

The connecting webs and front display panels 2 and 3 are together first folded forwardly upon the score lines 6 and 7, the 85 panels 2 and 3 being afterwards folded rearwardly upon the lines of scoring 9 and 10, and when the supporting ledge or bottom 12 is folded downwardly upon its score line 19, the slits 15 and 16 will take into the adjacent 90 cut-away portions of the webs 4 and 5, and the ledge or bottom will rest upon the shoulders 17 and 18 so that the device is easily and quickly put into the set up position, and a can of milk 11 or other article being 95 placed on the supporting ledge or bottom, the display is complete.

Of course any suitable printed matter may be placed upon the rear panel 1 so as to convey the desired message to the public in conjunction with the article of merchandise 11, whereby the entire parts of the panel contribute toward the one result of bringing to the attention of the public the knowledge of the article of merchandise displayed and the 105 various uses to which it may be put.

Although I have shown and described an ideal embodiment of my invention it is to be understood that I am not to be limited to the details herein shown and described, it being obvious that mechanical changes, within the scope claimed, may be made without departing from the spirit or sacrificing any of the advantages of the invention.

110 What is claimed is:—

A display device made of a single blank comprising a main display surface portion, two auxiliary display surface portions in front of the main display surface portion and substantially parallel with the main portion, intermediate connecting members substantially parallel with each other each hingedly connected with the central part of the main display portion and with the inner ends of each of the auxiliary display portions, leaving the outer ends of the auxiliary display portions free and a bracket member hinged to the main display portion and adapted to engage the connecting members at right angles thereto and to be held in 115 120 125 130

position thereby for supporting an article on
the bracket portion between the connecting
members and in front of the main display
portion and in back of the intermediate
auxiliary display portions and between the
intermediate connecting members, said
bracket portion holding the connecting mem-
bers and auxiliary display portions in the
aforesaid display position. In testimony that I claim the foregoing ¹⁰
as my invention I have signed my name
hereto.

JULIEN STRANDERS.
